WILLIAM M. PALMER, OF MIDDLEBUSH, NEW JERSEY.

Letters Patent No. 88,506, dated March 30, 1869.

IMPROVEMENT IN WATER-ELEVATORS.

The Schedule referred to in these Letters Patent and making part of the same.

To all whom it may concern:

Be it known that I, WILLIAM M. PALMER, of Middlebush, in the county of Somerset, and State of New Jersey, have invented a new and useful Improvement in Water-Elevators; and I do hereby declare that the following is a full, clear, and exact description of the same, reference being had to the annexed drawings, making part of this specification, in which—

Figure 1 is an elevation of my improved elevator, showing one of the buckets attached;

Figure 2 is a top view, showing the arrangement of the friction-pulleys, the clutch-couplings, and a portion of the mechanism for reversing or shifting the clutch-coupling;

Figure 3 is a sectional elevation on line *y y* of fig. 1; and

Figure 4 is a transverse vertical section on line *z z* of fig. 2.

Corresponding letters refer to corresponding parts in the several figures.

This invention relates to water-elevators for wells; and

It consists in the combination and arrangement of the parts for raising and lowering the buckets, and for retaining the buckets in any desired position within the well; and further, for furnishing the means of lowering the buckets further from the drums by which they are raised and lowered in case the water in the well falls to a lower level than that which it had previously occupied.

And it further consists in providing the buckets for drawing the water with an additional bail, and a weight, or a weighted bail, so arranged, with reference to said bucket, that it will insure the proper sinking of the bucket in the water, and cause the same to assume the proper position before leaving the water, to insure its being filled therewith.

A, in the drawings, represents the curb of a well, which may be of any suitable construction, which is adapted to receive the standards B, which support the windlasses, with the parts connected therewith.

B B represent standards, which are secured to the curb of the well, one upon each end thereof, they forming the bearings in which the journals of the windlasses run.

C represents the spout through which the water flows when delivered thereto from the bucket or buckets.

D represents the handle, or crank, which is placed outside the curb, but upon the end of the shaft which passes through the drums around which the rope or chain passes in raising the buckets.

E E' represent drums, which are to be made of wood, or of wood and metal united, those shown in the figure being of the last-named class, and having wooden centres, with a metallic head, or flange, upon their outer ends, while their inner ends are supplied with friction-pulleys, the office of which will be hereafter described.

F F' represent friction-pulleys, which have a V-

shaped groove formed in their peripheries, and which are bored out or otherwise fitted to the ends of drums E E', they serving the double purpose of a flange, or head, for the inner head of such drums and friction-rollers, to regulate the movements of the buckets.

G represents a rope or band, which passes around the friction-pulleys F F', and around sheaves, or pulleys I and H, which serve to hold the belt or rope in position.

H represents a sheave, or pulley, which is secured to an arm made fast upon a bar, or beam, which extends from one of the upper ends of the standards B to the other. This pulley is to be of such a diameter that a rope, chain, or strap, running in the V-shaped groove in its periphery, will be held at a proper distance apart to cause it to run in the grooved pulleys F F', and with binding or pressing either side of the same.

I represents a sheave, or pulley, which is attached to the bar, or beam above alluded to, by means of a spiral or other form of spring, which spring forms the bearings of a cross-arm, or shaft, which is formed upon the square portion of the arm upon which the pulley revolves. This pulley is so arranged, with reference to the friction-pulleys F F', that its axis of motion is midway between such pulleys, and it is to be of a diameter so much less than the pulley H, that the rope or belt G, which passes around both, and around the friction-pulleys, shall not come in contact with that portion which is travelling toward the pulley H while any other portion thereof is travelling toward pulley I. The office of the last-described pulley is twofold: first, as a consequence of its arrangement and its connection with the spring K, it serves to keep the rope or belt bearing upon the friction-pulleys to such an extent as to hold the buckets in any desired position in the range of their travel; and secondly, by simply pressing downward or inward upon it, the rope or belt will be so far released from its contact with the pulleys as to permit the strap or chain which winds around the drums, and is attached to the buckets, to be unwound, so that the bucket may be lowered in the well to accommodate the varying height of water therein, the hook a, fig. 1, being designed to retain the drum E in position while E' is being operated upon. The same effect may be produced by passing a pin through the curb and into the flange of the drum.

K represents the spring above alluded to, the construction and arrangement of which are clearly shown in fig. 1.

L represents a vertical lever, the lower end of which is pivoted to any convenient point upon the well-curb, its upper end extending above the same, and terminating in a suitable handle for operating the same, it being located upon that end of the curb which is nearest the crank of the windlass.

M represents a connecting-rod, which extends horizontally from the lever above referred to, to one arm of lever N, which is pivoted to the upper edge of the

curb, or to a standard secured thereto at a point midway between the pulleys F F', between which it passes, and is made to enter a groove formed in the double clutch O O', by means of its bifurcated ends. This lever has an arm extending at a right angle to the body thereof, and resting upon the upper edge of the curb, where it is guided in its movements by means of a clasp, or staple, placed over it and secured to the curb. The outer end of this lever is provided with a series of holes, to which the connecting-rod M may be attached.

O O' represent a double clutch-coupling, which, as above described, receives the end of lever N, by which it is moved upon the shaft D' of the windlass. This clutch is located centrally between the friction-pulleys F F', and, as it is moved to the right or left, engages with corresponding clutches formed upon the inner faces of such pulleys, the object of which arrangement is to enable the operator to raise either of the buckets and lower the other one at the same time, and without reversing the motion of the drums, by simply changing the position of the clutch, by means of braces L and N, thus causing the clutch to engage with either one or the other of the pulleys, at the pleasure of the operator.

P P' represent the clutches, formed as above described.

1 represents the bucket, which in fig. 1 of the drawings is shown as attached to the chain which winds around the drum E. This bucket may be made in any desirable form, and of any material which may be preferred; but when made of metal, its bottom should be of wood, for the purpose of facilitating the operation of "dipping" when it is lowered into the water. It however differs from other buckets in use, in that it has a weighted bail attached to it, at a point below its centre, the object of which is to cause the bucket to always assume a vertical position before it leaves the water, and thus insure its always being filled with the same. This weighted bail is attached to the bucket by means of loops, or rings, formed in its outer ends, while rings engage with a staple secured to the bucket, at parts above the centre of gravity thereof, and below the same at its respective ends, so that as its lower

end enters the water, the buoyancy of its bottom end shall cause it to tilt, and permit the water to flow in at the top end and fill it, when, in consequence of the bail proper being secured at a point above the centre of gravity, the tendency is to cause the bucket to assume a vertical position when the action of the windlass is brought to bear upon the same, which tendency is largely aided, and the accomplishment of the result made certain by means of the weighted bail.

2, in the drawings, represents the weighted bail above described, at which figure its arrangement, with reference to the bucket, is clearly shown. This bucket is provided with the usual projecting pins upon its upper end, for engaging with a rod, or bar of iron, which is attached to the curb at a suitable point for tilting said bucket, and emptying it of its contents as the buckets are raised.

Having thus described my invention, What I claim, and desire to secure by Letters Patent, is—

1. The combination and arrangement of the sheaves, or pulleys H I, spring K, and rope or belt G, substantially as and for the purpose described.

2. The parts enumerated in the above clause, in combination with the friction-pulleys F and F', substantially as shown and described.

3. The arrangement of the pulleys F F', drums E E', rope G, pulleys H and I, and spring K, for the purpose of regulating the position of the buckets with reference to the surface of the water in the well, substantially as shown and described.

4. The arrangement of the levers L N, double clutch-coupling O O', and clutches P P', substantially as and for the purpose described.

5. The bucket 1, having a weighted bail attached thereto, substantially as shown and described.

In testimony whereof, I have signed my name to this specification, in the presence of two subscribing witnesses.

WILLIAM M. PALMER.
